UNITED STATES PATENT OFFICE.

BENJAMIN F. ROUT, OF STANFORD, KENTUCKY, ASSIGNOR OF ONE-HALF TO
MARY ELLA HEWITT, OF SAME PLACE.

INCANDESCENT-ELECTRIC-LAMP FIXTURE.

SPECIFICATION forming part of Letters Patent No. 625,609, dated May 23, 1899.

Application filed August 2, 1898. Serial No. 687,550. (No model.)

To all whom it may concern:

Be it known that I, BENJAMIN F. ROUT, of Stanford, in the county of Lincoln and State of Kentucky, have invented a new and Improved Incandescent-Electric-Lamp Fixture, of which the following is a full, clear, and exact description.

This invention relates to improvements in fixtures for incandescent electric lamps; and the object is to provide a simple and comparatively inexpensive fixture by means of which a lamp may be used as an adjustable hanging lamp or as a stand-lamp.

I will describe an incandescent - electric-lamp fixture embodying my invention and then point out the novel features in the appended claims.

Reference is to be had to the accompanying drawings, forming a part of this specification, in which similar characters of reference indicate corresponding parts in all the views.

Figure 1 is a side elevation of a fixture embodying my invention with the adjusting-latch 19 omitted and showing the same as employed on a hanging lamp. Fig. 2 is a vertical section thereof. Fig. 3 is a plan view. Fig. 4 is a partial section and partial elevation showing the parts as arranged for a stand-lamp. Fig. 5 is an elevation of a portion thereof. Fig. 6 is a plan view thereof, and Fig. 7 is a perspective view of a portion of a shade-holding device employed.

Referring to the drawings, 1 designates a support one end of which passes through and is secured to a casing-section 2, which forms part of the casing for a winding-drum, as will be hereinafter described. At the other end of the support 1 is a ring 3, which is mounted to swing between arms 4. Seated in the ring 3 is a funnel-shaped guide 5, consisting, preferably, of insulating material—such, for instance, as porcelain or hard rubber—and through this guide the conductors 6 and 7 are passed.

The casing-section 2 consists of metal, hard rubber, or any other suitable material, and mounted on the section of the support 1, within the casing, is a winding-drum 8, which is connected by means of bolts 9 with a casing-section 10, consisting of any suitable mate-

rial and here shown as funnel-shaped. A spring 11 has one end connected to the support 1, which it will be understood is stationary as to rotary movement, and the other end of said spring is attached to one of the bolts 55 9 of the drum designed to wind the conductors 6 and 7, which pass around a pulley 12, placed in an opening in the side wall of the casing-section 2. It will therefore be seen that the drum and the casing-section 10 are 60 designed to rotate relatively to the section 2 of the casing. The pulley 12 is mounted in the bifurcated end of a bar 13, which is connected to the inner side of the section 2 of the casing, and bearing upon the side of the drum 65 8, adjacent to said section 2 of the casing, are rollers 14, supported in brackets secured to the section 2 of the casing.

It will be seen that the end of the bar 13 opposite that to which the pulley 12 is connected is curved over the flanged portion of the drum 8, and this curved portion is designed to prevent the conductors 6 and 7 from slipping off the drum. The inner ends of the conductors 6 and 7 extend through a rubber tube 15 and have the usual connections with circuit closing or controlling devices in the socket 16, designed to receive the base of the lamp 17. To accommodate the socket 16 to varying diameters or sizes of lamp-bases, 75 I provide it with spring-yielding fingers 18. Pivoted to the outer side of the section 2 of the casing is a latch or hook 19, designed to be engaged with the conductors, which are twisted together to hold the drum from rotation after the fixture shall have been adjusted to its desired position. 80

Rigidly secured to the support 1 is a plate 20, provided with radial slots through which legs 21 are movable. These legs are pivotally connected at their inner ends (see Fig. 4) to a disk or plate 22, mounted to slide on the support, and to prevent the plate or disk 22 from turning on the support the said support is made angular in cross-section and the 90 opening through the plate or disk is correspondingly shaped. Obviously by moving the plate or disk 22 toward the plate 20 the several legs may be caused to diverge to support the lamp in a standing position, as indicated. 100

cated in Fig. 4. During the adjustment of the lamp the guide 5 will swing and accommodate itself to the angle or deflections of the conductors, so that there will be little or 5 no danger of injuring the insulating material on the conductors by abrasion.

In operation when the device is used as a hanging lamp it may be drawn downward, causing the drum to rotate in a direction to 10 unwind the conductors, and this movement will of course wind the spring 11. When the lamp is in its preferred position, the latch or hook 19 is to be engaged with the cables and securely hold the parts as adjusted. Upon 15 releasing the cable from the latch or hook the spring by expanding will wind the conductors on the drum, and consequently draw the lamp upward.

When the lamp is used as a standing lamp, 20 it is designed to employ a suitable shade therewith, and preferably, as shown in the drawings, this shade will have a permanent connection with the fixture. The shade 23 may be made of metal, porcelain, or any other material which is suitable. Diametrically opposite metal straps 24 have their lower ends turned inward to receive the lower ends of the shade, and the upper ends of these straps have screw-threaded portions 25, which pass 25 through openings in clips 26, which engage over the top edge of the shade, and above these clips nuts 27 are engaged with the screw-threaded portions of the straps. The shade is supported by arms each consisting of two 30 telescopic sections 28 and 29. The section 28 of the arm has swinging connection with the lower end of the strap 24, and the section 29 at its lower end has pivotal connection with a clip 30, secured around the socket 16. To 35 the upper end of the section 29 of the arm is secured a loop 31, which engages around the section 28, and to the lower end of the section 28 is secured a loop 32, which engages around the section 29 of the arm. Therefore 40 these sections may slide relatively to each other. To hold the sections in their extended adjustment to support the shade, I employ 45 spring-latches 33, the ends of which are connected to the loops 31 and are designed to 50 engage over the loops 32, as plainly indicated in Fig. 4.

In Fig. 4 the full lines show the position of the parts when the shade is in use on the standing lamp. Dotted lines in Fig. 4 show it as 55 moved to a position adjacent to the section 10 of the casing. To prevent the shade from falling downward when the lamp is suspended, as in Figs. 1 and 2, I employ the finger 34, which has pivotal connection with the band 60 or clip 30 and is designed to be swung outward, so that the shade may rest thereon.

It is obvious that a lamp-fixture embodying 65 my invention may be made as ornamental as desired, and as the greater portion of the conducting-wires are within the casing during the day they will be fully protected from dirt or dust.

Having thus described my invention, I claim as new and desire to secure by Letters Patent—

1. A lamp-fixture, comprising a support, a casing-section rigidly mounted on said support, a casing-section mounted to rotate relatively to the fixed section, a drum secured to the rotatable section and designed to receive and wind the electric conductors, a spring for moving the drum and rotatable section in one direction, and a socket on the rotatable section for receiving the base of an electric lamp, substantially as specified. 80

2. An incandescent-electric-lamp fixture, comprising a support, a casing-section rigidly connected to said support and having an opening through its side wall, a pulley in said opening a drum mounted to rotate on the support 85 within the casing, a casing-section secured to said drum, a spring for rotating the drum in one direction, a roller around which the conductors are designed to pass when extended through the opening in the first-named casing-section, and rollers supported by said first-named casing-section and bearing upon the drum, substantially as specified.

3. An incandescent-lamp fixture, comprising a support, a casing-section rigidly mounted on said support, a drum mounted to rotate on the support within the casing, a casing-section secured to the drum, a spring for rotating the drum in one direction, a plate attached to the support outside the casing and having an opening, a plate or disk mounted to slide on the support, and legs having swinging connection with said disk and movable through openings in the plate secured to the support, substantially as specified. 105

4. An incandescent-lamp fixture, comprising a support, a casing-section rigidly mounted on said support and having an opening for the passage of conductors, a guide mounted to swing on the support and through which the conductors pass, a winding-drum on the support within the casing and on which the conductors wind, and a casing-section secured to said drum, substantially as specified. 110

5. An incandescent-lamp fixture, comprising a support, a casing, a drum mounted to rotate on the support within the casing, a spring for rotating said drum in one direction, and a shade having adjustable connection with the casing, substantially as specified. 115

6. An incandescent-lamp fixture, comprising a support, a casing, a winding-drum in the casing, arms consisting of telescopic sections and having pivotal connection with a 125 clip on a socket extension of the casing, and a shade having pivotal connection with said arms, substantially as specified.

7. In a lamp-fixture, a casing having a socket to receive an incandescent lamp, a collar or clip secured to said socket, arms consisting each of two sections mounted to slide one relatively to the other, one section of each arm having pivotal connection with said col- 130

lar or clip, and a shade having pivotal connection with the other sections of said arms, substantially as specified.

8. An incandescent-lamp fixture, comprising a casing, a socket on said casing, a clip or collar engaging around said socket, shade-supporting arms each consisting of two sections, one section having pivotal connection with the clamp or collar and each section hav-

ing a loop to engage around the other section, a spring-latch for engaging with the loops to hold the arm-sections as extended, and a shade having pivotal connection with the arms, substantially as specified.
